UNITED STATES PATENT OFFICE.

EDWARD ERMOLD, OF NEW YORK, N. Y.

BOTTLE-CORKING MACHINE.

SPECIFICATION forming part of Letters Patent No. 427,258, dated May 6, 1890.

Application filed May 1, 1889. Serial No. 309,298. (No model.)

To all whom it may concern:

Be it known that I, EDWARD ERMOLD, of the city, county, and State of New York, a citizen of the United States, have invented certain 5 new and useful Improvements in Bottle-Corking Machines, of which the following is a specification.

This invention relates to an improved bottle-corking machine which is driven by power 10 and operated in connection with a treadle whenever the machine is to be started for work, the release of the treadle interrupting the machine; and the invention consists of a bottle-corking machine in which all the operative parts are driven by cams of a cam-shaft, 15 said cam-shaft being engaged by a clutch with the driving-shaft whenever the treadle is lowered, so as to bring the machine in operation and released from said driving-shaft when 20 the treadle is released.

The elements of my corking-machine are a cork-guiding chute, a reciprocating squeezer guided below said tube, a vertically-reciprocating plunger, a cork-supplying hopper provided with means for feeding the corks into the feed-chute, an intermittently-actuated cork-arresting pin that stops the corks in the feed-chute, so as to supply them snugly into the path of the squeezer, which presses the 25 corks in the guide-tube into the path of the plunger, and of a bottle-rest vertically below the cork-guide tube and plunger, said bottle-rest being operated in connection with the plunger, whereby said bottle-rest is held rigidly in position for forcing the cork into the mouth of the bottle.

The invention consists further of certain details of construction and combination of parts and details, as will be fully described 40 hereinafter, and finally be pointed out in the claims.

In the accompanying drawings, Figure 1 represents a side elevation of my improved bottle-corking machine. Fig. 2 is a vertical 45 longitudinal section of the same on line $x-x$, Fig. 4. Fig. 3 is a front elevation of the machine. Fig. 4 is a horizontal sectional view of the same on the line $v-v$, Fig. 2. Figs. 5, 6, and 7 are details of the clutch mechanism by which 50 the cam-shaft of the machine is connected with the power-shaft. Fig. 8 is a side elevation of the mechanism for supporting the ar-

resting bottle-rest, drawn on a larger scale, parts being in section and others broken out. Fig. 9 is a detail horizontal section on line $y-y$, 55 Fig. 8. Fig. 10 is a side elevation, partly in section, of the cork-arresting pin and squeezer. Fig. 11 is a top view of the squeezer with a part broken out and the cork-chute in section. Fig. 12 is a front elevation of the squeezer, 60 the cork guiding and compressing tube being removed; and Figs. 13 and 14 are a vertical longitudinal section and a vertical transverse section of the bottom throat of the hopper and feed-roller by which the corks are fed 65 in regular manner to the feed-chute.

Similar letters of reference indicate corresponding parts.

In the drawings, A represents a bottle-support, which is placed vertically below the cork guiding and compressing tube B and the vertically-reciprocating plunger C, that is guided in a fixed guide-sleeve C' above the cork guiding and compressing tube B. In the open rear part of the cork guiding and compressing 75 tube is arranged a horizontally-reciprocating squeezer D.

The parts enumerated—namely, the bottle-rest, cork-guiding tube, plunger, and squeezer—have been used in different arrangements in bottle-corking machines heretofore, and I do not claim the combination of these parts broadly. The new features of my machine, however, consist in operating the movable parts referred to from a power-shaft 80 and in supplying the corks by an automatic feed, which forms the essential individual feature of my machine.

The automatic cork-feed consists of an inclined cork-feeding chute E, which extends 90 from the rear part of the cork-guiding tube B in upward direction to the delivery end of a throat F' at the bottom of a supply-hopper F, in which the wet corks are placed. The rear part of the throat F' is provided with an opening, in which is arranged a roller F², that is slightly concaved and provided with alternating teeth or fingers F³ on the circumference, so as to take hold of the corks fed or passing from the hopper into the throat and 95 feed the same in downward direction into the supply-chute E. The supply-chute is formed of a series of parallel rods, which are supported by circular collars E' at the top 100.

and bottom, the upper one being attached to the lower end of the throat F', while the lower one is attached to the wider rear part of the cork guiding and compressing tube B. These 5 rods exert less friction on the corks than glass or metal tubes, as the wet corks cannot adhere to the same, and are readily fed in downward direction to the squeezer.

At the lower part of the feed-chute is arranged 10 a horizontally - reciprocating and spring-actuated shank or rod e, carrying on its end the cork-arresting pin G, which can enter between the rods of the feed-chute E and engage intermittently one of the corks 15 in said feed-chute, so as to arrest the downward movement of the same until the one below the arresting-pin is dropped in front of the squeezer and fed by the same to the front part of the cork guiding and compressing 20 tube B.

The cork guiding and compressing tube, the squeezer, and cork-arresting device are supported on the table A³, that is attached to the top of the frame A', while a second table 25 or platform A⁴ is supported by standards a⁶ on the table A³, said platform A⁴ being provided with the guide-sleeve C' for the plunger-rod C.

On the platform A⁴ are arranged upright 30 standards A⁵, which are provided with bearings for the feed-roller F² of the supply-throat F', and said standards, in connection with the feed-tube E, support the feed-throat and its feed-roller F², as shown in Figs. 2 and 3.

35 The cam-shaft S' is provided with two cams S² and S³, the cam S² operating the plunger, while the cam S³ operates the squeezer D.

The plunger-rod C' is connected by a pivot-link with the front end of a fulcrumed lever 40 C², the rear end of which is connected by a pivot-link with the vertically-guided rod C³, which is provided on its lower end with an anti-friction roller resting on the cam S³, as shown in Fig. 2, and is kept in contact with 45 the same by a spiral spring C⁵, that is connected with an arm C⁶, projecting from the rod C³, and to a transverse rod of the supporting-frame A', as shown in Fig. 2.

The shank D' of the squeezer D is guided in 50 a suitable box d² on the table A³, and is provided at its rear end with an anti-friction roller in the same manner as the plunger-operating rod C³, said roller being held in contact with the cam S³ by a spiral spring S⁴, secured to the squeezer and to the guide-box d² of the same.

On the top of the guide-box of the squeezer is arranged a fixed guide-sleeve d³, in which is guided the shank or rod e of the cork-arresting pin G, which shank is provided with an adjustable collar e³, between which and the sleeve d³ is interposed a spiral spring e⁴, by which the cork-arresting pin is moved in the direction toward the cork-chute E. The 65 front end of the shank of the cork-arresting pin G is guided in a fixed sleeve e⁶, supported on the top of a guide-frame G', which serves to

steady the motion of the squeezer. The rear end of the shank e of the cork-arresting pin G is connected by a pivot-link g with a fulcrumed lever g', the lower end of which is engaged by a nose g² at the rear end of the shank D of the squeezer, as shown clearly in Figs. 2 and 10. When the squeezer is moved forward, the nose g² engages the lower end of the lever g', and thereby withdraws the shank of the cork-arresting pin, and thus also withdraws the pin G from the feed-chute E, and permits the dropping of a cork below said pin through the collar E' above the squeezer. 75 As soon as the squeezer is released and returned or moved backward by its spring S⁴, the cork-arresting pin G is moved forward again by its spring e⁴, so as to enter the next following cork and retain the entire column 80 of corks in the feed-chute in position until they can be fed in downward direction by the next forward motion of the squeezer. In this manner one cork after the other is fed in a regular and reliable manner to the squeezer 85 and cork guiding and compressing tube.

The squeezer D is provided with a T-shaped bar d at its rear end, said bar being provided with guide-rods d', which are guided in openings of the transverse frame G'. The 95 frame G' is open at its middle part, so as to permit the passage of the squeezer-shank.

The cork guiding and compressing tube B is wider at its rear part than at its front, and is attached to the frame G'. It is provided on 100 its under side at its front part with a downwardly-tapering segmental flange b, which forms a rest for the bottle-neck, while the upper edge of the bottle-mouth rests against an outwardly and downwardly inclined lip b' 105 of the tube B, which flange b and lip b' form a flaring mouth, as shown clearly in Fig. 10.

The fulcrumed plunger-operating lever C² is connected by a pivot-rod with a weighted lever H, pivoted to lugs A⁶ on the under side 110 of the bracket A² of the machine-frame. The lever H is provided with a slot or opening H', into which a gripping-jaw H² projects from the pivoted end of said lever, the end of which jaw is applied to the shank a of the bottle-support A whenever the plunger begins its downward motion, so that the shank of the bottle-rest is engaged by said jaw and rigidly locked by the same against the pressure exerted by the plunger. The more the plunger 115 is lowered the stronger will the shank of the bottle-support be gripped and the firmer the same be held in position against the pressure exerted on the same by the plunger.

The shank a' of the bottle-support A is further 120 engaged by the forked end of a fulcrumed and weighted lever l, which is pivoted to arms A' of the lugs A⁶, said lever l engaging a fixed box a² on the shank a, said box being provided with grooves in its sides, and which 125 grooves have convex lips that are engaged by the convex ends of the forked lever l. The lever l balances the weight of the bottle-support and serves to lift the same as soon 130

as the plunger recedes, and the jaw H^2 is raised by the lifting action exerted by the plunger-lever C^2 on the lever H . By this lifting action of the lever the bottle-mouth is pressed 5 against the flanged lower end of the cork guiding and compressing tube B , and is thereby in a position for receiving the cork.

The driving-shaft S is provided at one end with a fly-wheel M , which acts as a pulley, to 10 which the driving-belt is applied. The cam-shaft S' , which is in line with the driving-shaft S , is provided on its outer end with a disk M' , against which is pressed a spring-actuated brake-shoe M^2 on the upper end of 15 a spring-actuated rod M^3 , which form together a brake by which the motion of the shaft S is steadied, so as to neutralize the concussions and shocks which are exerted by the same on the squeezer and plunger. The spring-actuated 20 brake-rod M^3 is guided in socket-sleeves of the supporting-frame A' , as shown clearly in Fig. 1. On the cam-shaft S' is also located a pulley p , which by a cross-belt p' , passes over a pulley p^2 on the shaft of the feed- 25 roller F^2 and serves to impart rotary motion to said feed-roller, as shown in Fig. 1.

The connection of the cam-shaft S' with the driving-shaft S , which latter is continuously rotated by the belt and fly-wheel, is 30 made by means of a clutch device which is shown in Figs. 5, 6, and 7. This clutch device is operated by a treadle T , which is pivoted to the lower part of the supporting-frame A' and connected with a rod t , provided 35 at the upper end with a clutch mechanism. The treadle is guided by a stirrup t' at the lower part of the frame A' and returned to the raised position by a spiral spring t^2 . As soon as the treadle is released the spiral 40 spring t^2 raises it and places the upper beveled end t^3 of the rod t in such position as to press back the spring-actuated interlocking jaw m of one member of the clutch and prevent it from engaging recesses m' on the hub 45 of the fly-wheel M , which forms the other members of the clutch. As soon as the treadle is depressed and brought into its normal direction the beveled upper end of the rod t is withdrawn, so that the spring-actuated jaw m 50 can engage the recesses m' in the hub of the fly-wheel and produce thereby the interlocking of the clutch members and the rotating of the cam-shaft S' . As long as the treadle is depressed by the foot the working parts of 55 the corking-machine are operated, while the moment the treadle is released the motion of the cam-shaft is stopped, while the rotary motion of the fly-wheel M and its shaft continues. In this manner the operation of the 60 corking-machine is quickly and easily interrupted or established and thereby the corking-machine fully in the control of the operator.

The advantages of my improved corking-machine are as follows:

First. Owing to the agitating-rollers in the supply-hopper of the corking-machine, the

corks are fed in a regular manner into the feed-chute of the corking-machine, they being kept in continuous motion by said roller, so as not 70 to stick to each other or the walls of the hopper. The cams on the roller furthermore force one cork after the other into the feed-chute, so as to produce in connection with the reciprocating arresting device the regular 75 supply of one cork after another to the squeezer and plunger.

Secondly. Owing to the open form of the chute, the corks are always in view, so as to indicate whenever a new supply of corks is 80 necessary.

Thirdly. The arresting device prevents in a simple and reliable manner the forward feeding of more than one cork at a time, as it arrests all the corks in the feed-chute above the 85 one dropped in front of the squeezer. As soon as the arresting device is released another cork is permitted to drop, while the entire column of corks above the said one is fed downward until the lowermost cork is stopped 90 again by the arresting device.

Fourthly. The bottle-supporting device is so arranged that in case of more than an ordinary pressure the bottle-platform yields sufficiently to prevent the bursting of the bottle, 95 by which considerable damage is experienced by the power bottling-machine heretofore in use.

Fifthly. By the clutch device the corking-machine can be interrupted at any moment 100 or started again by the simple operation of the treadle.

Having thus described my invention, I claim as new and desire to secure by Letters Patent—

105

1. In a bottle-corking machine, the combination of a bottle-compressing tube, a reciprocating plunger adapted to work therein, a bottle-support provided with a shank, a frame having an opening in which said shank rises 110 and falls, a pivoted weighted lever below said frame and connected by a rod with an oscillating lever attached to the reciprocating plunger, and a second weighted pivoted lever having one end engaging a fixed box on the 115 shank of the bottle-support.

2. In a bottle-corking machine, the combination, with a bottle-supporting platform, of a counterbalancing weighted lever engaging the shank or stem of said platform, a forked 120 and pivoted lever provided with a jaw that can engage the shank of the platform, a reciprocating plunger, and a vertical rod connecting the operating-lever of the plunger with the above-mentioned lever provided with the 125 jaw, substantially as set forth.

3. The combination of a fixed cork-guiding tube having a flaring mouth formed on its bottom, a bottle-supporting platform vertically below said tube, a vertically-reciprocating plunger above said cork-guiding tube, a weighted balancing-lever connected to the shank of the bottle-platform, a pivoted locking-jaw engaging said shank, a weighted le- 130

ver connected with the locking-jaw, and a rod connecting the jaw-operating lever with a plunger-operating lever, so as to produce the locking of the bottle-platform in position 5 when the plunger is raised, substantially as set forth.

4. The combination, in a bottle-corking machine, of an actuating cam-shaft having cams for working the different parts of the machine, 10 a brake-wheel at one end of the shaft, and a spring-actuated brake applied to said brake-wheel for the purpose of neutralizing the concussions of the cams and operating parts, substantially as set forth.

15 5. In a bottle-corking machine, the combi-

nation of the chute and the table A³, the compressing-tube B, the squeezer D, provided with a nose or projection g² near its inner end, the cork-arrester G with shank-bar, the pivoted lever g', pivotally connected to the shank-bar of the said cork-arrester, a rotary shaft, and a cam on said shaft for operating the said squeezer.

In testimony that I claim the foregoing as my invention I have signed my name in presence of two subscribing witnesses.

EDWARD ERMOLD.
